UNITED STATES PATENT OFFICE.

GUSTAVE A. KING, OF CHICAGO, ILLINOIS.

PUZZLE.

1,295,521.

Specification of Letters Patent. Patented Feb. 25, 1919.

Application filed May 16, 1918. Serial No. 234,888.

To all whom it may concern:

Be it known that I, GUSTAVE A. KING, a citizen of the United States, residing at Chicago, in the county of Cook and State of Illinois, have invented new and useful Improvements in Puzzles, of which the following is a specification.

The puzzle device which is the subject matter of the present application for patent consists of two flexible interlocked, strips, one of which is bent to form the letter **S**, the object being to change this strip into the letter **C** without removing it from the other strip.

In order that the invention may be better understood, reference is had to the accompanying drawings forming a part of this specification, and in said drawings,

Figure 1 is a plan view of one of the members of the puzzle;

Fig. 2 is a plan view of the other member, and

Figs. 3 to 8 are perspective views illustrating the manner in which the puzzle is solved.

Referring specifically to the drawing 10 and 11 denote two strips of paper or other flexible material and of suitable length. The strip 10 has three longitudinally spaced slits 12 running in the direction of the length of the strip, and it is adapted to be bent into a sigmoidal curve to obtain the letter **S**, and strung on the strip 11 by passing the latter through the slits 12. The problem then is to change the letter **S** to the letter **C**, or into unciform shape, without removing it from the strip 11. This is accomplished in the following manner:

The curved strip 10 is first moved along the strip 11 to come close to the lower end thereof as shown in Fig. 4; next, the upper part of the strip 11 is curved back and down so that its ends overlap as shown at A in Fig. 5; the strip 11 being now in the form of a loop, circle or oval; next, while the lapped ends A are held between the thumb and fore-finger of one hand, the other hand pulls the upper part of the **S** back over and down the remote section of the looped strip 11, as shown in Fig. 6; next, the portion B, B, B of the **S** is turned in the direction of the arrows of Fig. 6 to appear as at

B¹, B¹, B¹ in Fig. 7; and, finally, the portion B¹, B¹, B¹ of the **S** is raised closer to the joint or lap A of the strip 11 to assume 55 the shape of the letter **C**, as shown in Fig. 8.

The strip 11 also contains the following inscription "Cubs vs. OX". When the strip 10 has the **S** form, this letter, combined with "OX" on the strip 11, forms the word "Sox" 60 the popular designation of a well known base ball club, the letters O, X, appearing between the convolutions of the strip 10. When the strip 10 is given the **C** shape, this letter, combined with the letters U, B, S, 65 on the strip 11, spells the word "Cubs" the popular designation of another well-known base ball club. Various other inscriptions may be applied to the strip 11 to form words when combined with the letter strip 10, and 70 the latter strip may contain inscriptions such as advertising matter, etc. The device can be so cheaply manufactured that it may be used as an advertising novelty.

I claim:

1. A puzzle comprising a pair of flexible, interlocked strips, one of the strips being strung on the other strip in a sigmoidal curve, and being changeable thereon into unciform shape without removal from the 80 strip.

2. A puzzle comprising a pair of flexible, interlocked strips, one of the strips being strung on the other strip in a sigmoidal curve and having slots through which said 85 other strip passes, the curved strip being changeable into unciform shape without removal from the strip on which it is strung.

3. A puzzle comprising a pair of flexible, interlocked strips, one of the strips being strung on the other strip in the shape of the letter **S**, and being changeable thereon into the shape of the letter **C** without removal 90 from the strip.

4. A puzzle comprising a pair of flexible, 95 interlocked strips, one of the strips being strung on the other strip in the shape of the letter **S**, and being changeable thereon into the shape of the letter **C** without removal from the strip, the second mentioned strip 100 having inscriptions which are completed by being combined with the letter strip.

In testimony whereof I affix my signature.

GUSTAVE A. KING.
